UNITED STATES PATENT OFFICE.

WALENTY M. PRZYBYLA, OF PULAWSKI, MICHIGAN.

DESIGN FOR A MONEY BAG.

61,421.

Specification for Design.

Patented Aug. 29, 1922.

Application filed December 3, 1921. Serial No. 519,771. Term of patent 3½ years.

To all whom it may concern:

Be it known that I, WALENTY M. PRZYBYLA, a citizen of the United States, residing at Pulawski, in the county of Presque Isle and State of Michigan, have invented a new, original, and ornamental Design for a Money Bag, of which the following is a specification, reference being had to the accompanying drawing, forming a part thereof.

The figure is a perspective view of a money bag, showing my design.

I claim:

The ornamental design for a money bag, substantially as shown.

In witness whereof, I affix my signature.

WALENTY M. PRZYBYLA.
